ABSTRACT

A hermetic compressor comprising compression mechanism and a motor for driving the piston means within the compression mechanism, with the motor being supported directly in the outer housing of the compressor by mounting means including a laminate formed integrally with the stator of the drive motor.

COMPRESSOR CONSTRUCTION

RELATED APPLICATION

This is a continuation, of application Serial No. 223,437 filed Feb. 4, 1972 now abandoned. BACKGROUND OF THE INVENTION

This invention relates to a hermetic compressor for use in refrigeration systems or air-conditioning applications having an improved electric drive motor construction incorporating integrally formed mounting means for the compression mechanism and motor.

In the past, hermetic compressors have been made with a compression mechanism comprising a crankcase portion with cylinders therein and an annular portion for receiving and housing therein the electric drive motor for the drive shaft for moving pistons within the cylinders. The annular portion is a part of the compression mechanism casting. Such construction is relatively bulky and expensive and a number of different attempts have been made in order to reduce the weight of the compression mechanism casting and to reduce cost of manufacture of such compressor.

An object of the present invention is to provide an improved hermetic compressor having an electric drive motor wherein the stator is constructed and arranged so as to materially reduce the size and cost of the compression mechanism casting and thus reduce the overall cost of the compressor.

Another object of the present invention is to provide an improved hermetic compressor with a stator having mounting means integrally formed thereon so as to mount the stator within the outer casing of the hermetic compressor.

Yet another object of the present invention is to provide an improved hermetic compressor which includes an electric drive motor having a stator formed from laminates bonded to one another, with at least one of the laminates constructed and arranged so as to provide mounting means to support the stator in the outer casing, together with the compression mechanism secured thereto. Other objects and advantages of the present invention will become more apparent hereafter.

BRIEF DESCRIPTION OF THE DRAWING

There is shown in the attached drawing a presently preferred embodiment of the present invention wherein like numerals refer to like elements in the various views and wherein:

FIG. 1 is an elevation view of an improved compressor embodying the present invention, with parts broken away to better show the internal construction;

FIG. 2 is an end view of the improved compressor of FIG. 1, with parts broken away;

FIG. 3 is a plan view of the improved compressor of FIG. 1, with parts broken away;

FIG. 4 is an elevation cross-sectional view of the compression mechanism casting of the present invention;

FIG. 5 is a plan view of the compression mechanism casting;

FIG. 6 is an end view of the compression mechanism casting;

FIG. 7 is a cross sectional view of the improved stator of the electric drive motor of the present invention;

FIG. 7a is an enlarged detail view of a portion of the improved electric drive motor illustrating a mounting

means laminate structure having an inside radius substantially equal to that of the laminates comprising the stator;

FIG. 7b is an enlarged detail view of a portion of a modified electric drive motor illustrating a mounting means laminate structure cut-away at the inside radius to provide for improved electric characteristics;

FIG. 8 is a plan view of the improved stator of the electric drive motor of FIG. 7;

FIG. 9 is an elevation view of a modified compressor, with parts broken away;

FIG. 10 is an end view of the modified compressor of FIG. 9, with parts broken away;

FIG. 11 is a plan view of the stator of the electric drive motor employed in the compressor of FIG. 9; and

FIG. 12 is a cross sectional view of the stator of FIG. 11.

DETAILED DESCRIPTION OF THE PRESENT INVENTION

Referring to FIGS. 1, 2 and 3, there is illustrated a hermetic compressor embodying the present invention. The compressor 10 comprises a gas-tight outer housing including an upper shell 12 and a lower shell 13, integrally joined to one another as, for example, by welding.

If desired, a plurality of legs (not shown) may be secured to the bottom of the exterior surface of the lower shell 13 so as to support the compressor in an upright position within a condensing unit or an air-conditioning unit.

Resiliently supported within the outer housing or casing of the compressor 10 is a compression mechanism 16 which includes the novel electric motor of the present invention. The compression mechanism includes a compressor block or body 18 having a base portion 19 and a crankcase portion with cylinders 20 defined therein for receiving pistons 22. The pistons 22 are adapted to be reciprocated within the cylinders 20 by means of a drive shaft 24 journalled within the compressor body or block 18. Connecting rods 26 operatively connect the pistons 22 to the drive shaft.

Provided at the end of each cylinder 20 is a discharge and suction valve assembly 28. Each discharge and suction valve assembly 28 is comprised of a discharge valve unit and a suction valve unit operative in a known manner to control the flow of refrigerant gas to and from the cylinders 20. Head means 29 enclose the end of each cylinder 20.

The lower end of drive shaft 24 is journalled in lower hub plate 39 that is secured to the body or block 18 by suitable means, for example, bolts 41. Thrust washer 43 held in place by plate 45 takes up the drive shaft thrust.

It will be understood that the returning suction gas from the suction line of a refrigeration system will enter the outer casing of the compressor 10 and pass upwardly over the electric drive motor 34 which includes a stator 36 and a rotor 38, into suction shroud 33 and through the conduits 30 and 32 into the cylinders 20, wherein the gas is compressed and then discharged through the discharge and suction valve assemblies 28 into the head area 40 of each cylinder. From the head area, the gas passes into the discharge mufflers 42 and then into discharge line 44 for communication to the discharge line of the refrigeration system.

During operation, rotation of the drive shaft 24 will cause oil in the sump formed in the bottom of the lower

shell 13 to be ingested into the opening in the drive shaft 24 and forwarded to the various shaft journal surfaces and connecting rod bearing surfaces that require lubrication.

An important feature of the present invention is the construction of the stator of the electric drive motor 34 wherein a portion of the stator serves as the main support with the outer casing for the compression mechanism 16 and motor 34. This construction results in a materially reduced weight of the compressor as the annular motor support portion of prior castings can be obviated by the present design. Essentially, in the present design a laminate 36b of the stator 36 functions as a portion of the support for the motor 34 and compressor block 18. The laminate 36b includes mounting means which cooperate with resilient spring means 46 to mount the compression mechanism resiliently within the outer housing of the compressor 10. Elongated bolts 55 extend through openings 57 in the stator 36 for connecting the stator to the tapped holes 56b in the mounting projections 56 on compressor block 18.

The resilient means 46 include a coil spring 62 disposed between a bracket 63 secured to the lower shell 13 of the outer casing and an ear of the laminate 36b of motor 34. Bolt 64 extends through each opening 60 in the laminate 36b and is secured to bracket 63 so as to maintain the parts in assembled relationship.

With reference to FIGS. 4, 5, 6 and 8, there is illustrated a compression mechanism casting of the present invention. The compression mechanism block or body 18 includes a base portion 19 from which the cylinders 20 depend. In the illustrated embodiment of the present invention, a two-cylinder casting is shown.

Extending upwardly and downwardly from the central portion of the base 19 is a journal hub 50 having bearing liners 52 positioned therein for journaling the drive shaft 24. The mounting projections 56 extend upwardly from the base portion 19, and as best seen in FIG. 5, there are four projections 56 extending upwardly from the compressor block in the embodiment illustrated. Dowel pins (not shown) extend from openings 56c into openings 37 in the stator in order to properly align the motor 34 on the compressor block casting 18.

Openings 58 and 59 corporate with suction conduits 30 and 32 to admit suction into suction gas into cylinder 20.

Considering now FIGS. 7, 7a and 8, there is illustrated an electric drive motor 34 embodying principles of the present invention. The motor 34 is comprised of a stator 36 and a rotor 38 (not shown) adapted to be rotatably mounted within the stator and inductively coupled thereto. The stator 36 of motor 34 is comprised of laminates or layers 36a of sheet metal or like magnetic properties, which were heretofore welded to one another and which are presently often secured by epoxy bonding, with end windings secured to the stator laminates to complete the winding for the stator. The laminates 36a are epoxy bonded or similarly joined to one another so as to minimize any power losses resulting from the welding process heretofore employed and to eliminate motor laminate noise.

A feature of the present invention is the use of a thicker laminate 36b forming a part of the laminated stack of stampings. The laminate 36b provides a part of the mounting means for the electric drive motor 34 and compressor block 18 within the outer casing. As

shown, the laminate 32b is provided with holes 60 in the corners thereof which are adapted to cooperate with the resilient means 46 to support the motor 34 and compression mechanism 16 secured thereto within the outer casing of the compressor 10.

Turning to FIG. 7b, there is illustrated a modified form of electric drive motor 134 incorporating a laminate 136b in the stator lamination 136a. In this construction, the inner portion of the laminate 136b is cut outwardly so as to have larger inside radius than the laminations 136 of the stator. In some applications, this construction will provide less power losses than would result from the construction of FIG. 7a.

The material savings resulting from utilizing a compression mechanism incorporating an improved motor as shown by the present invention is evidenced by the following test information which indicates that a compressor embodying the improved motor and compression mechanism casting is capable of producing 72,000 BTU/HR capacity at 45°F evaporator coil and 125°F condensing - 65°F return gas and zero sub-cooling as compared with a known comparable compressor which is capable of producing 58,000 BTU/HR capacity at the same conditions. The casting of the present invention weighs one-half that of the casting of the compressor having 58,000 btu capacity. Casting fabrication is materially simplified and in addition, a substantial savings is effective in cost of materials.

With reference to FIGS. 9, 10, 11 and 12 there is illustrated a modified compressor incorporating a new and novel mounting arrangement for the compressor mechanism. The compressor 210 includes resilient mounting means 246 disposed in the compressor such that the mounting plane (the plane through laminate 236b) is above the center of gravity of the compression mechanism 216. This arrangement provides for greater mounting stability of the compression mechanism 216 within the outer casing.

In general, the remaining components of compressor 210 are the same as those in compressor 10 and accordingly like numerals have been applied to like elements in the various views with the exception that the numerals in FIGS. 9, 10, 11 and 12 are preceded by the numeral 2. Thus the shell or outer casing portion is identified as 12 in FIG. 1 and 212 in FIG. 9.

The new and novel mounting system for the compressor mechanism provides for greater mounting stability of the compression mechanism by allowing the mounting plane of the compression mechanism to be above or substantially the same as the center of gravity of the compression mechanism. This improvement is not being used currently in refrigerant compressors known to me.

There has been provided by the present invention an improved hermetic compressor incorporating a novel electric drive motor having means for mounting same directly on the body of the compression mechanism and directly to the interior of the outer casing of the compressor. The mounting means are readily fabricated as a part of the stator without materially adding to the cost thereof. In a preferred form of the invention, the laminations of the stator are epoxy-bonded to one another with the result that noise sometimes attendant to the welding of laminations and the thermal cracking or shock occurring in welded laminates one to the other is obviated. As a result of use of the present invention, substantial savings result in fabrication of the

hermetic compressor since the fabrication can be accomplished by the step of resiliently supporting the stator of the drive motor directly from the outer casing, while at the same time supporting the compression mechanism on the electric drive motor and improving the stability of the compressor mounting system.

While I have described a preferred embodiment of my invention, it will be understood that my invention is not limited thereto since it may be otherwise embodied within the scope of the following claims.

I claim:

1. A hermetic compressor comprising an outer housing, a body defining cylinder means, piston means disposed in said cylinder means, a drive shaft operatively connected to the piston means for moving same, a motor secured to the drive shaft for rotating same, said motor including a stator operatively affixed to the body and a rotor operatively connected to the drive shaft, the motor incorporating resilient mounting means for supporting same in the outer housing, said stator comprising a plurality of laminates secured to one another, said mounting means comprising a laminate formed integral with said stator, the plane of said laminate being above or substantially the same as the center of gravity of the body and aligning means for aligning the stator on the body disposed between the stator and the body.

2. A compressor as in claim 1 wherein bracket means are provided in the compressor, and spring means are positioned between the bracket means and the mounting means for resiliently supporting said body and

motor in the compressor.

3. A compressor as in claim 1 wherein the plane of said laminate is above the center of gravity of the body.

4. A compressor as in claim 1 wherein the body comprises a base portion with at least one cylinder means thereon.

5. A compressor as in claim 4 wherein projections extend from said base portion for cooperatively engaging with said stator.

10 6. A compressor as in claim 4 wherein said aligning means comprise dowel means.

7. A hermetic compressor comprising an outer housing, a body defining cylinder means, piston means disposed in said cylinder means, a drive shaft operatively connected to the piston means for moving same, a motor secured to the drive shaft for rotating same, said motor including a stator operatively affixed to the body and a rotor operatively connected to the drive shaft, the motor incorporating resilient mounting means for directly supporting same within the outer housing, said stator comprising a plurality of laminates secured to one another, said mounting means comprising a laminate formed integral with said stator, the plane of said laminate being above or substantially the same as the center of gravity of the body, said body requiring less material than a comparable body that has a portion encircling the stator and aligning means for aligning the stator on the body.
